United States Patent

Des. 242,377
Patented Nov. 16, 1976

242,377

RING

Jan Meyer, 3420 Mount Diablo Blvd.,
Lafayette, Calif. 94549

Filed Dec. 20, 1974, Ser. No. 534,998

Term of patent 14 years

Int. Cl. D11—01

U.S. Cl. D11—29

FIG _ 1

FIG _ 7

FIG_2

FIG_3

FIG_4

FIG_5

FIG_6

FIG. 1 is a perspective view of the ring showing my new design;

FIG. 2 is a front elevational view on a reduced scale from the scale of FIG. 1;

FIG. 3 is a top plan view of the ring on a further reduced scale from the scale of FIG. 2;

FIG. 4 is a left side elevational view thereof;

FIG. 5 is a right side elevational view thereof;

FIG. 6 is a bottom plan view thereof; and

FIG. 7 is a rear elevational view thereof.

I claim:

The ornamental design for a ring, as shown and described.
